UNITED STATES PATENT OFFICE.

CARL A. KALLNBACH, OF DETROIT, MICHIGAN, ASSIGNOR TO THE KALLNBACH AUTOMATIC FIRE ALARM COMPANY, OF CLEVELAND, OHIO, A CORPORATION OF OHIO.

ALARM SYSTEM.

1,212,958.

Specification of Letters Patent. Patented Jan. 16, 1917.

Application filed May 8, 1913. Serial No. 766,251.

To all whom it may concern:

Be it known that I, CARL A. KALLNBACH, a citizen of the United States, residing at Detroit, in the county of Wayne and State 5 of Michigan, have invented a new and useful Improvement in Alarm Systems, of which the following is a specification, the principle of the invention being herein explained and the best mode in which I have 10 contemplated applying that principle, so as to distinguish it from other inventions.

My invention has general reference to an alarm system and more particularly to a duplex automatic electric fire alarm.

15 The object is the provision of a mode for effecting the desired results more efficaciously and yet involve structural details which will be simple and economical of manufacture.

20 My inventive conception involves two types of alarm intended for coöperative use. A number of outlying automatic alarm sounding devices are intended for distribution about the premises which it is proposed 25 to safeguard against fire. In addition one or more alarm indicating devices are disposed at a central point or a corresponding number of places to which direct and ready access may be had. These are preferably 30 accompanied as a unit structure with one of the sounding types. Coincidently with the starting of a fire near any one of the alarm sounders, such that the particular one is operated, the more or less distant indicator designates the location in which the fire 35 has originated.

The inventive conception is embodied in means which are hereinafter explained and variously defined in the claims, while the 40 annexed drawing and particular description thereof together set forth in detail one certain means constituting my invention, the disclosed means however, being but one of various mechanical forms in which the principle of my invention may be applied.

45 Referring next to the drawing in which like figures of reference designate like parts throughout the several views: Figure I is an elevation of one part of my invention, the 50 front of the casing being removed. Fig. II shows a side view of the same. Fig. III represents a complementary part associated with the part first seen, on a reduced scale and with the casing intact. Fig. IV is a 55 diagrammatic view of but one system in its

entirety of the eight according to this exemplification.

Sounding device.—This is the part which has been first mentioned and as best seen in Fig. I is the device which is adapted to automatically sound an alarm when sufficiently close to the source of heat. The operation or closing of the actuating circuit is brought about by either one or possibly both of two thermostats, hence the use of the word duplex. The provision of two thermostats is merely to foster the added dependence which one is thereby warranted in placing upon the alarm. By preference, and as shown, one is designed to fulfil its function 60 in advance of the other. Proceeding now to the description of this specific device as represented in Figs. I and II, it comprises a casing 1 having a rear supporting portion 65 adapted to be fastened in some approved manner to a wall or other fixture, a curved shield 2 secured thereto below, and a forward compartment 3. This latter is open below and has a removable cover 4. An electric bell including a magnet 5, gong 6 70 and hammer 7 is operatively mounted near the top of the supporting portion 2 and is electrically connected through the medium of lead wires 8 and 9. Below the bell are a pair of forwardly projecting symmetrical 75 brackets 10 provided at their ends with fixing screws 11.

Thermostats.—Some distance below and in line with each of the brackets 10 are two other brackets 12 having upturned forward 80 extremities 13 directly below the respective ends of the brackets 10. The extremities 13 are fashioned with platinum coated cones 14. These cones are electrically connected by terminal wires each numbered 15. Any 85 approved type of mercury thermometer 16 is suspended from the frame 1 as is best seen in Fig. II. The lower end is fashioned with a bulb 17 disposed behind the shield 2 and between the brackets 12. The thermometer tube is graduated according to the Fahrenheit scale as suggested. Another 90 terminal wire 18 connects electrically with the mercury and is attached in the bulb 17 by means of a simple set screw 19. A 95 weighted member 20 extends across the front of the thermometer near its top. Depending from opposite ends of the member 20 are a pair of tubes 21 insulated above 100 at 22. These tubes are platinum lined in- 110

teriorly and are in gravitational alinement respectively with the cones 14 upon which they may be snugly seated by reason of their restricted dimensions. The upper ends of the tubes 21 though necessarily below the insulation 22 are in turn electrically connected by a single terminal wire 23^a 23^b extending through the thermometer. Secured upon the upper surface of the weighted member 20 by a thumb screw is a mass of fusible alloy 24 of a chemical character such that it will melt at the comparatively low temperature say between 175 degrees and 200 degrees Fahrenheit. It will now be apparent that the member 20 and hence the tubes 21 may be held in a suspended position by means of two wires 25 firmly connected each with the alloy 24 and one of the fixing screws 11 upon the brackets 10. It should also be manifest, assuming a battery in circuit, by what set of elements two thermostatic combinations are established. To explain: Assuming the single circuit which could be established from so much of my system as has been thus far described and assuming further the presence somewhere in such circuit of a battery, it will be seen that the thermostat in one case is the column of mercury itself. This column rising by reason of its proximity to the heat, comes eventually, and preferably at a point somewhat over 150 degrees Fahrenheit, in contact with the wire 23^a 23^b. Inasmuch as the mercury column constitutes in effect one terminal, since directly connected with the terminal wire 18, the joining of the two terminals necessarily serves to close the circuit. To follow the circuit as controlled by this particular thermostat, around from the battery through the sounding device and back to the battery, reference may be had to the diagrammatic view seen in Fig. IV. It will there be seen that this particular circuit has been designated, as a part of the first acting thermostat, by the letters W, W' and W². Leaving the battery B at the left, the current passes upwardly through the wire 8 into the magnet coil, then out along the wire 9 and downwardly across the wire portion 23^a and then again downwardly through the mercury column and the wire 18 and finally back to the other end of the battery. Assuming again substantially this same single circuit with its battery, it will be seen that the thermostatic control in the other case is the fusible alloy 24 which on melting, permits the fall of the tubes 21 until they rest upon the cones 14 thereby again automatically closing the circuit. The circuit in this case merely includes in part substitution for and in part addition to the W' portion of the circuit which is really the wire portion 23^a; the W² portions or terminal wires 15 each of which connects with the wire leading back

to the return end of the battery. Inasmuch as the fusible alloy 24 melts only at the higher temperature stated, it is obvious that the thermostat of which it forms a part independently closes the circuit, subsequent to the time it is intended that the upward movement of the mercury column as a part of the first acting thermostat shall effect this result.

Indicating device.—In the form seen in Fig. III this complementary part of my system combines, besides its own different features, all of those just considered in connection with the description of the enlarged details of Figs. I and II. It will be understood however that the two devices need not be associated in a single structure. Proceeding then to the description of the distinct features only, it will be seen that in the nature of an index chart is provided. The compartment 3 is altered by the addition of lateral spaces 26 and 27 and a top space 28 while the cover 4 is correspondingly broadened to include lateral extensions 29 and 30. These are provided with openings, as it happens for the exemplifying purpose in hand, with four openings each. These openings may be covered with glass slides upon which appear indicia of the eight localities on the premises at each of which it was decided to place one of my sounding devices. As represented, those on the left beginning at the top are meant to indicate, "barn," "rear of building," "2nd stairway" and "1st stairway"; whereas those on the right again reading down in order indicate, "attic," "2nd floor," "1st floor" and "basement." Fitted over the extra top space 28 is another glass upon which appears the word "Fire." Under each of the nine glass slides just mentioned and which may be assumed to be removable, is an electric lamp. The lamp 31 under the word "Fire" is electrically connected in parallel via a connection which I have designated by the letters Y Y' with every one of the eight W, W', W² and necessarily with every one of the eight W, W', W², W³ circuits. On the other hand, each of the other eight lamps 32 is in series with the lamp 31 while similarly connected in parallel with only one particular circuit W, W', W², W³, that is with only one particular one of the eight outlying sounding devices such as is shown in Fig. IV. For the purpose of illustrating in what manner this double alarm system may be operated by either of two successively operating thermostats, it has been taken for granted that a fire has gained headway in the "rear of building," likely the kitchen. Reference to the diagrammatic view seen in Fig. IV clearly shows how the operation of either thermostat would include the connection Y Y' in parallel and simultaneously light the lamps under "Fire" and "R."

Operation.—But little concerning the operation of the system as a whole need be said in view of the explanation as to the interrelation of the two devices which has gone before. However, to consider two instances very briefly: fire starting in the kitchen which falls under the heading "R" presently causes the temperature to rise and in due course the mercury in the thermometer of the particular sounding device located for the purpose in or sufficiently near such room. Directly the mercury column comes into contact with the wire 23 the bell should be sounded in the kitchen and at the same moment the two lamps in the indicating device under "Fire" and "R" are lighted. If any person on the premises does not happen to be in the kitchen but hears the bell which is ringing not knowing precisely where it is, he can step to the central point where the indicating device is properly located and at once ascertain the approximate location where the fire originated. It is merely in the event that the fire should happen to find its origin nearer the location of the indicating device than any of the outlying sounding devices and to avoid therefore an additional sounding device adjoining the indicating device that the two have been combined. In case such a circumstance occurred, the two distinct circuits W , W' , W^2 and Y , Y' would be similarly connected in parallel save that all connections would be established within the confines of a single casing.

Mention may properly be made of the possibility of connecting my alarm system with the same battery or set of batteries which supply the current for the ordinary electric bell system generally in vogue and involving push buttons. When these two differently purposed systems are thus connected with the same source of current, a testing facility is afforded for ascertaining whether my alarm system is capable of

operating when needed. In short, under the circumstances considered, every time one pressed a push button of a door bell and found it working, he could *ipso facto* rely upon a satisfactory working of my system. 50

My invention being thus described with sufficient thoroughness, what I desire to secure by Letters Patent and therefore claim specifically is:

1. An alarm system comprising the combination of a plurality of electric circuits each provided with a pair of successively operating thermostats and an annunciator, said circuits furthermore having connected in parallel therewith respectively, each its 60 individual signal and all additionally one common signal. 55

2. An alarm system comprising the combination of a plurality of circuits, a common signal connected in series with each of 65 said circuits, a particular signal connected in series with each such circuit, a local signal connected in parallel with each such circuit, and a corresponding number of pairs of thermostats for successively controlling 70 said circuits respectively, and each adapted invariably to effect three distinct signals simultaneously. 75

3. An alarm system comprising in combination, a plurality of outlying electric circuits each including a pair of local thermostats and a local annunciator, and a corresponding number of lines connected in parallel therewith respectively, each of said parallels including a common signal and a 80 distinct designating signal, said common signal and all of said designating signals being placed together. 80

Signed by me, this 25th day of April, 1913.

CARL A. KALLNBACH.
